UNITED STATES PATENT OFFICE.

WILLIAM H. LONDERGON, OF CHICAGO, ILLINOIS.

DESIGN FOR AN ERASER.

SPECIFICATION forming part of Design No. 19,628, dated January 28, 1890.

Application filed November 30, 1889. Serial No. 332,165. Term of patent 14 years.

To all whom it may concern:

Be it known that I, WILLIAM H. LONDERGON, a citizen of the United States, residing at Chicago, Illinois, have invented and produced a Design for Erasers, of which the following is a specification.

The leading feature of my design is a black-board-eraser having an erasing-surface A, provided with a handle-block B, presenting in outline a diamond form or shape. The diamond-shaped eraser presents the design.

I claim—

The design for an eraser herein shown, consisting of a diamond-shaped erasing-surface provided with a handle-block, substantially as described.

WILLIAM H. LONDERGON.
